United States Patent Office

Des. 210,428
Patented Mar. 5, 1968

210,428

CAMERA FOR INFRARED PHOTOGRAPHY OR SIMILAR ARTICLE

Tohru Karikawa, Tokyo, Japan, assignor to Asahi Kogaku
Kogyo Kabushiki Kaisha, Itabashi-ku, Tokyo-to, Japan

Filed Jan. 27, 1967, Ser. No. 5,585

Term of patent 14 years

Claims priority, application Japan Aug. 16, 1966

(Cl. D61—1)

Fig. 3.

Fig. 4.

Fig. 4.

FIG. 5.

FIG. 6.

FIG. 1 is a front elevational view of a camera for infrared photography or similar article, showing my new design;

FIG. 2 is a top plan view;

FIG. 3 is a rear elevational view;

FIG. 4 is a bottom plan view;

FIG. 5 is a side elevational view; and

FIG. 6 is an opposite side elevational view thereof.

Portions of the drawing figures are diagonally lined to indicate transparency.

I claim:

The ornamental design for a camera for infrared photography or similar article, as shown and described.
